UNITED STATES PATENT OFFICE

FRANK W. BRINTNALL, OF DETROIT, MICHIGAN, ASSIGNOR, BY MESNE ASSIGNMENTS, TO NATIONAL AUTOMOTIVE FIBRES, INC., OF WILMINGTON, DELAWARE, A CORPORATION OF DELAWARE

UPHOLSTERY MAKING MACHINE

Application filed October 17, 1928. Serial No. 313,075.

This invention relates particularly to upholstery making machines adapted to the purpose of making pleated upholstery. The invention is especially useful in an upholstery machine for making pleated cushions, such as are largely used in automobiles.

The primary object of the invention is to provide a machine of the character indicated with mechanism adapted to provide the lining material with pre-formed U-shape seams or ridges in an improved manner.

The invention contemplates providing the sheet of lining, as it is fed through the machine, with U-shape ridges which are progressively formed from the central portion of the sheet outwardly toward the lateral edges. The purpose is to permit the material to be properly gathered by the ridge-formers, a ridge or ridges at the central portion of the sheet being first produced, and ridges flanking the central ridge or ridges being progressively formed from the center of the sheet outwardly toward the lateral edges.

In my application, Serial No. 278,234, filed May 16, 1928, I have disclosed mechanism adapted to produce a similar effect on the finish fabric, or cover, of the cushion; and the mechanism for properly seaming the lining, which is disclosed in the present application, is most usefully employed in association with means for gathering and pleating the finish fabric.

The present invention is illustrated in a preferred embodiment in the accompanying drawings, in which—

Fig. 1 is a broken vertical sectional view of an upholstery machine embodying the invention; Fig. 1^a is a broken sectional perspective view illustrating the type of cushion which the machine is adapted to produce; Fig. 2 is a broken transverse vertical sectional view, taken as indicated at line 2-2 of Fig. 1; Fig. 3 is a broken plan sectional view, taken as indicated at line 3 of Fig. 1; Fig. 4 is a detail sectional view, taken as in-

dicated at line 4 of Fig. 1; Fig. 5 is a similar section, taken at the lower point, as indicated at line 5 of Fig. 1; Fig. 6 is an elevational view of a grooved seam-forming member employed; and Fig. 7 is an elevational view of a companion member having a tongue or projection adapted to extend into the groove of the member shown in Fig. 6.

A machine of the general construction to which the present invention relates is fully disclosed in Brintnall and Ross application, Serial No. 310,588, filed October 5, 1928.

In the construction illustrated, A designates the frame of an upholstery machine; B, a series of ridge-forming chains upon which the finish fabric, or cushion-covering, designated 1, is carried through the machine; C, a pair of rolls at the front portion of the machine adapted to draw the work through the machine; D, a vertically adjustable cross-head upon which certain of the operative parts are mounted; D', castings carried by the end-portions of the cross-head D and rigidly connected together by cross bars, or shafts, D², D³, D⁴ and D⁵; E, a grooved forming-roll journaled in the cross-head and vertically adjustable therewith, said roll being provided with a series of circumferential grooves 2 adapted to accommodate the nested seam-ridges of the fabrics and the ridge-chains carrying the same, the lining fabric being designated 3; F, a batt-feeding device journaled in the members F' carried by the cross-head and vertically adjustable therewith; G, a batt-deflecting roll journaled in the members F'; H, a series of tubes mounted on a member H' carried by the main frame and serving to conduct batting strips 4 to the pleats of the cushion being formed; I, a batt-feeding device journaled in the members I' carried by the main frame; J, a cross bar, or fixed shaft, carried by the main frame; K, a series of sewing mechanisms adjustably mounted on the cross-head D and capable of being raised and lowered therewith; L, a se-

ries of pairs of seam-ridge forming members adapted to progressively form seam-ridges in the lining from the central portion of the lining outwardly as the lining is drawn to the forming roll E, where the nesting of the seam-ridges of the finish fabric within the seam-ridges of the lining fabric is effected; and M, a series of devices mounted on the stationary cross bar J and cooperating with the ridge-chains B to form the covering, or finish fabric 1 into pleats and intervening seam-ridges as the finish fabric is drawn or carried through the machine.

The ridge-chains B, the work-feeding roll 15 C, the forming roll E, the feed devices F, the batt-deflecting roll G, and the sewing mechanisms K are positively driven by suitable means (not shown). Likewise, the feeding device I is positively driven by suitable 20 means (not shown) which may be periodically stopped so as to hold the batting strips, while they are torn or severed over shearing edges 5 with which the lower ends of the chutes or guides H are provided.

25 Referring to Fig. 1^a, it may be stated that in the operation of the machine, the lining 3 is provided with a series of longitudinal seam-ridges 3^a, and the covering, or finish fabric, 1 is provided with a series of seam-ridges 1^a and pleats, or pipes, 1^b. The seam-ridges 1^a are nested within the seam-ridges 3^a and the nested seam-ridges project above the plane of the lining so as to afford opportunity for the sewing of the seam-ridges. To 30 effect the sewing, each of the sewing mechanisms K is provided with a transversely reciprocating sewing needle 6 and a co-operating looper needle 7 which works in a plane parallel with the seam-ridges. Each sewing 40 needle carries a sewing thread 6^a, and each looper needle carries a looper thread 7^a.

The manner in which the sewing mechanisms K operate need not be described in detail. These mechanisms form no part of 45 the present invention, specifically. It may be stated that Fig. 1^a illustrates the formation of a lock-stitch seam.

It should be understood that in the operation 50 of the machine, a series of pleats or pipes is formed as the fabrics are drawn through the machine, and a strip of cotton batting, or other suitable material, enters each of the pleats, the strips of batting being properly secured in the pleats when the seam-ridges 55 are sewed in the manner illustrated in Fig. 1^a. Each pair of formers L comprises a grooved front member L' provided with hooks or lugs 8 and 9, by means of which the member is demountably carried by the 60 fixed shafts D² and D³ of the cross-head; and a rear member L² equipped with lugs or hooks 10 and 11, by means of which the member is demountably supported on the fixed shafts D⁴ and D⁵ of the cross-head. The rear 65 member of each pair is provided with a pro-

jection or flange 12 which is adapted to extend into the groove or vertical slot 13 of the companion member L'.

The upper ends of the flanges 12 are beveled, as indicated at 12^a in Figs. 1 and 7; and, as appears from Figs. 1 and 2, the two ridge-formers at the central portion of the machine and immediately flanking the central line 14 (Fig. 2) have the flanges 12 extending highest. From the central portion of the machine towards the sides of the machine, the flanges 12 are successively reduced in height. The purpose is to permit the lining to be gathered first at the central portion, and then successively in both directions from the center in the operation of forming the seam-ridges in the lining. This insures positive and even gathering of the lining fabric to form the seam-ridges.

As shown in Fig. 2, it is preferred to equip the shafts D² with members 15 having fingers 15^a and 15^b adapted to yieldingly grip the edges of the lining fabric, but permitting the fabric to be gradually withdrawn as the shirring operation proceeds. The lining 3 is shown supported by cross bars or shafts 16 and 17 carried by standards 18 mounted on the end portions of the cross-head. The lining is drawn from a roll 19, shown brokenly in Fig. 1.

In the operation of the machine, the finish fabric and the lining fabric are fed or drawn through the machine; the lining fabric is provided with seam-ridges at intervals corresponding with the grooves in the forming roll E; the finish fabric is provided with seam-ridges and intervening pleats (fullness of the cloth); the finish fabric seam-ridges are nested within the lining seam-ridges as the material passes beneath the forming roll E, the ridge-chains B serving to carry the seam-ridges through the grooves of the roll E; the batting strips 4 enter the pleats between the finish fabric and the lining and are carried therewith beneath the forming roll E; and, finally, the sewing of the seam is effected by the sewing mechanisms K.

In practice, the sewing mechanisms are adjustably spaced, and provision is made for adjusting the position of the grooves 2 of the forming roll E. In the illustration given, the grooves constitute spaces between collars 20 with which the roll E is equipped. Various other members, including the formers M, are adjustably spaced. The purpose of the adjustability is to enable cushions with pleats of different widths to be formed in the machine. The pairs of forming devices, or ridge-formers, L are likewise laterally adjustable upon the shafts which carry them. Also, the pairs of formers are readily detachable to enable access to be gained to the work, when necessary. When the lining is to be entered between the members of the formers L, the rear members L² may be re-

moved until the lining has been properly introduced through the machine, and the members L² may then be replaced.

As will be seen from Figs. 5 and 6, the lower portion of the bar 12 tapers rearwardly, as indicated at 12^b, thus forming a divider between the strips of batting. Also, as seen in Fig. 1, the lower portion of the bar 12 extends into the groove 2 of the forming roll E.

As shown in Fig. 3, the shafts D² and D⁴ are equipped with adjustably mounted sleeves or rings 21 which are provided with peripheral grooves 21^a which receive the hook portions of the forming members L¹ and L². The forming members may be properly spaced by adjusting the members 21.

The foregoing detailed description has been given for clearness of understanding only, and no unnecessary limitations should be understood therefrom, but the appended claims should be construed as broadly as permissible, in view of the prior art.

25 What I regard as new, and desire to secure by Letters Patent, is:

1. In an upholstery machine: means for feeding a lining sheet, a covering, and intervening batting strips, said means comprising devices for forming pleats and intervening seam-ridges in the covering; and a series of pairs of devices for forming seam-ridges in the lining, each pair comprising a grooved member and a companion member which is provided with a projection extending into the groove of the first-mentioned member.

2. In an upholstery machine a bed and associated means for providing a covering with pleats and intervening seam-ridges; a grooved forming-roll above and co-operating with said bed; means for conducting batting strips to the pleats; and means for conducting a lining to said forming-roll and forming seam-ridges in the lining, said last-named means comprising a series of ridge-forming devices having co-operating tongues and grooves so disposed as to progressively form the ridges in the lining from the central portion outwardly.

3. In an upholstery machine: a bed equipped with means for supporting a covering and having means for forming pleats and intervening seam-ridges in the covering; means disposed over said bed for feeding batts to the pleats; a vertically adjustable cross-head disposed over the bed; and a series of pairs of ridge-forming members mounted on said cross-head, said members being equipped with means for forming ridges in a lining conducted therethrough to the vicinity of the bed of the machine.

4. In an upholstery machine for forming pleated upholstery; a bed; a vertically adjustable cross-head above said bed; cross bars carried by said cross-head; and ridge-form-

ing members demountably carried by said cross bars.

5. In an upholstery machine for forming pleated upholstery; a bed; a vertically adjustable cross-head; a forming roll journaled in said cross-head; and a series of pairs of fabric-ridging members mounted on said cross-head and equipped with ridge-forming means so disposed as to progressively form ridges in the fabric from the central portion thereof outwardly as the fabric is drawn therethrough.

6. In an upholstery machine: a vertically movable cross-head; cross bars carried thereby; and a series of pairs of ridge-forming members mounted on said cross bars, each pair comprising a grooved member and a companion member having a tongue projecting into the groove of the first-mentioned member.

7. In an upholstery machine: a vertically movable cross-head; a forming roll journaled in the lower portion of said cross-head and equipped with a series of peripheral grooves; ridge-forming means supported on said cross-head above the plane of said forming roll and equipped with a series of fabric-ridging devices; and means for conducting fabric to said ridge-forming means.

8. In an upholstery machine, the combination with means for feeding a covering and strips of filling material and forming the covering into pleats and intervening seam ridges, of a series of gathering and ridging members disposed over the path of the covering and filling material, for gathering a lining sheet drawn between said members and forming seam ridges therein, said ridging members being of progressively decreasing length from the middle of said series outwardly to the outermost members of said series whereby the middle portion of the lining will first contact with the longest of said ridging members and the latter will progressively form seam ridges in the lining from the central portion thereof outwardly as the same is drawn between said members.

9. In an upholstery machine: a bed equipped with means for supporting a covering and having means for forming pleats and intervening seam-ridges in the covering; means disposed over said bed for feeding batts to the pleats; a cross-head disposed over said bed; a forming device mounted on said cross-head having spaces for the passage of seam-ridges therethrough; means for conducting a lining-fabric; and seam-ridge forming devices in front of which the lining passes comprising members having portions projecting into said spaces, said members decreasing in height progressively from the central portion of the machine towards the sides, whereby the middle portion of the lining will first contact with the longest member and said members will progressively

form seam-ridges in the lining from the central portion thereof outwardly as the lining passes through the mechanism.

10. An upholstery machine as set forth in
5 claim 9, in which the members of the seam-ridge forming devices are mounted on said cross-head.

11. An upholstery machine as specified in
claim 9, in which the means for feeding batts
10 comprise toothed members disposed over and
engaging the batts and in which the members
of the seam-ridge forming devices are inter-
posed between said toothed members and
said first-mentioned forming device.
